UNITED STATES PATENT OFFICE.

SAMUEL J. GOFF, OF DALLAS, IOWA.

WASHING-MACHINE.

1,154,242.

Specification of Letters Patent. Patented Sept. 21, 1915.

Application filed June 4, 1914. Serial No. 843,097.

To all whom it may concern:

Be it known that I, SAMUEL J. GOFF, a citizen of the United States, and resident of Dallas, in the county of Marion and State of Iowa, have invented a certain new and useful Washing-Machine, of which the following is a specification:

The object of my invention is to provide a washing machine of simple, durable and inexpensive construction, in which a clothes holding device within the tub is swung or reciprocated.

More particularly it is my object to provide such a device having an agitating device of the kind mentioned of extremely simple and inexpensive construction; and including a clamping bar for holding the clothes against the portion of the agitating device within the tub, and having also suitable simple means for controlling the clamping bar from a point outside the tub.

Still a further object is to provide such a controlling device mounted on and adapted to move with the movable parts of a machine; so that the whole agitating device has a minimum number of friction points on the body of the machine.

My invention consists in certain details, in the construction, combination and arrangement of the various parts of the device, whereby the objects contemplated are attained, as hereinafter more fully set forth, pointed out in my claims, and illustrated in the accompanying drawing, in which:

Figure 1 shows a side elevation of a washing machine, embodying my invention. Fig. 2 shows a vertical, transverse, sectional view through the same. Fig. 3 shows a top or plan view of the machine. Fig. 4 shows a horizontal, sectional view, taken on the line 4—4 of Fig. 2, and Fig. 5 is a horizontal, sectional view, taken on the line 5—5 of Fig. 2. Fig. 6 is a detail, sectional view, taken on the line 6—6 of Fig. 2, and shows the manner in which the oscillating member is pivoted to the cover member.

In the accompanying drawing, I have used the reference numeral 10 to indicate the body of an ordinary washing machine tub, resting upon supporting legs 11, having an ordinary hinged cover 12. The agitator of my improved washing machine is of the type which is pivoted in the cover and adapted to swing in the interior of the tub on its pivotal point. The agitator, which is indicated generally by the reference character A, is a

U shaped device having the horizontal member 13 within the interior of the tub, and the parallel upwardly extending arms 14, extending upwardly through the tub cover to 60 points spaced above the tub cover.

The agitator is pivotally mounted in the following manner: In the upper surface tub cover is a transverse groove, in which is received a rod 15, having loops 16 formed at 65 its ends receiving the upright members 14 which are fixed in said loops to permit the agitator A to swing to and fro in the tub 10 when the shaft 15 rocks. Mounted on the upper surface of the cover 12 and adapted to 70 cover the groove which receives the rod 15, is a suitable plate 17 having slots 17^a therein to permit proper movement of the parts.

It will be understood that any suitable means for pivoting the agitator in the movable cover may be employed.

Formed on the upper ends of the members 14 are loops 18. Extended through the loops 18 is one member 19 of the agitator controlling device, the other sides of which 80 are indicated generally by the reference characters 20 and 21.

The handle is preferably substantially rectangular as shown, or otherwise formed so that the portion 20 is of such length as to 85 allow the operator to use the machine from a choice of positions. On the member 20 may be a suitable roller 20^a to give a better hand hold. Slidably mounted on the members 14, in the interior of the tub 10, is a 90 clamping bar 24. Secured to the clamping bar 24, approximately at the middle thereof, is an upwardly extending rod 25, extending through the cover 12 to a point above the same. The lower surface of the cover 95 12 is provided with suitable slots 26 to permit the swinging motion of the members 14 and 25. Pivoted to one of the upright members 14, above the cover 12, is a lever 27, which extends adjacent to and beyond the other member 14 and is pivoted to the upper end of the member 25. The last mentioned member 14 is provided with a plurality of notches 28 and a pawl 29 is pivotally secured to the member 27 and designed to selectively engage the notches 28 to hold the members 24, 25 and 27 against upward movement.

The lever 27 is preferably composed of parallel members, slightly spaced from each other, as shown in Fig. 4, said members being pivoted at one end to one of the upright members 14 and receiving be-

tween them at their other end the other member 14. The portions of the lever 27 which extend beyond the last mentioned member 14 are brought together and form a handle 30.

In the practical operation of my improved washing machine the clamping member 24 is raised by means of the member 25 and lever 27 and the clothes are placed between the agitator member 13 and the clamping member 24 and the clamping member is pressed toward the member 13, against the clothes. When the member 24 is pressed tightly against the clothes, the pawl 29 is moved to engage the upper notch 28 and the clothes then are clamped firmly in position. It will be seen that the member 24 may be clamped in various positions, as shown for instance by the dotted lines and by the full lines in Fig. 2, for holding different quantities of clothes or other articles to be washed.

The advantages of a construction such as that shown in my drawing are numerous. The parts are of comparatively simple and inexpensive construction; the agitator device is mounted to swing readily and easily in the tub cover and the clamping bar fastening means is so mounted and arranged on the agitator device that it is not necessary to secure it in any direct way to the tub body or cover, whereby I have been able to produce a machine having the fewest points of contact and therefore the fewest points of friction possible on the tub body or cover. On account of the use of the rectangular member, comprising the members 19, 20 and 21, I am enabled to secure a rigid construction for properly bracing and spacing the upper ends of the members 14 and giving a handle which may be operated from a variety of positions.

It will be understood that some changes may be made in the details of the construction of my machine, without departing from

its essential features, and it is my intent to cover by this application any such changes which may be included within the scope of the following claims.

I claim as my invention:

1. In a device of the class described, a tub body, a hinged cover thereon, an agitating device comprising a shaft rotatably mounted in the cover, a horizontal member within the tub body and upright members fixed to said shaft and adapted to tilt when the shaft is rocked, means for imparting reciprocal motion to the upper ends of said upright members, a clamp slidably mounted on said upright members within the tub, a rod pivoted to said clamp and extended upwardly through the cover, a lever pivoted at one end to one upright member above the cover, means on the other end of said lever for engaging the other upright member at different points thereon for locking the lever against upward movement.

2. In a device of the class described, a tub body, a hinged cover thereon, an agitating device comprising a shaft rotatably mounted in the cover, a horizontal member within the tub body and upright members fixed to said shaft and adapted to tilt when the shaft is rocked, means for imparting reciprocal motion to the upper ends of said upright members, a clamping bar slidably mounted on said upright members within the tub, a rod secured to said clamping bar and slidably mounted in the tub cover, means mounted on one of the upright members for raising and lowering said clamping bar, and means on said last mentioned means for engaging the other upright member at different points thereon for preventing upward movement of said clamping bar.

Des Moines, Iowa, April 22, 1914.

SAMUEL J. GOFF.
